[57] CLAIM

The ornamental design of an airbrush spray booth, as shown.

DESCRIPTION

FIG. 1 is a front elevational view of an airbrush spray booth embodying my new design;

FIG. 2 is a rear elevational view thereof;

FIG. 3 is a top plan view thereof;

FIG. 4 is a bottom plan view thereof;

FIG. 5 is a side elevational view thereof as seen from one side;

FIG. 6 is a side elevational view thereof as seen from the other side;

FIG. 7 is a perspective view thereof as seen from the front and to one side thereof;

FIG. 8 is a perspective view thereof as seen from the rear and from the other side; and

FIG. 9 is a cross-sectional view thereof as seen on the section line 9—9 of FIG. 1.
